POCKET LIGHTER

William E. Evans, Waterbury, Conn., assignor to
 The Waterbury Lock & Specialty Company,
 Milford, Conn., a corporation of Connecticut

Application August 26, 1939, Serial No. 291,993

3 Claims. (Cl. 67—7.1)

This invention relates to improvements in pocket lighters and particularly to pocket lighters provided with a wick-burner for cigars or cigarettes and a torch for lighting a pipe.

One object of the invention is to provide a pocket lighter in which the wick-burner and torch are both supplied with burning fluid from a single chamber.

Another object is to provide a reservoir or fluid chamber open at its lower end to facilitate filling, and an outer casing open at its upper end and adapted to receive the reservoir so as to securely close the same.

Still another object is to provide the torch with a wick tube extending into the fluid chamber.

With the above and other objects in view, as will appear to those skilled in the art from the present disclosure, this invention includes all features in the said disclosure which are novel over the prior art.

In the accompanying drawing, in which certain modes of carrying out the present invention are shown for illustrative purposes:

Fig. 1 is a side view of a pocket lighter constructed in accordance with my invention;

Fig. 2 is a top view of the same with the cover open;

Fig. 3 is a sectional view on the line 3—3 of Fig. 2;

Fig. 4 is a perspective view of the torch detached;

Fig. 5 is a broken sectional view of the burner end of the torch tube;

Fig. 6 is a broken perspective view of the inner end of the torch tube;

Fig. 7 is a sectional view on the line 7—7 of Fig. 6;

Fig. 8 is a perspective view of a torch wick-holding plug; and

Fig. 9 is a perspective view of the cover spring detached.

In carrying out my invention I employ a main reservoir 11 closed at its upper end by a top plate 12 and a correspondingly shaped outer casing 13 closed at its lower end by a cap 14 which forms the bottom of the lighter. These members fit closely one within the other but permit excess gas to escape between them. Mounted in the top plate is a tube 15 which receives a flint 16 and a spring 17 which is held in the tube by a screw-plug 18. The flint is forced by the spring against a friction-wheel 19 which is mounted between the walls 20 and 21 of a guard 22. In the top plate a wick 23 is mounted in a collar

24 around an opening 25 in the top plate 12 to form a burner or wick-burner. Also secured to the top plate is a spring 26 having an upward extension 27 and an inwardly-extending lip 28. Pivoted to the guard 22 above the spring is a cover 29 carrying an extinguishing-cup 30 and adapted when closed to cover and extinguish the wick 23. The spring is formed with a clearance-slot 31 for the purpose as will hereinafter appear. Also mounted in the cap is a torch-reservoir in the form of a torch-wick tube 32 which contains a wick 33 which terminates at its outer end short of the outer end of the tube which is closed by a cap 34 having a small perforation 35 to form a torch or torch-burner, leaving a gas chamber 36 in the outer end of the torch tube.

The wick extending through the torch-tube has its end 37 projecting beyond the inner end of the tube 32, which wick at that point is compressed and held by a plug 38 flattened on one side. On the tube 32 is a tapered plug 39 which sets into a collar 40 struck inward from the top plate 12, the outer end of the tube 32 extending through the clearance-slot 31 in the spring 26. It will be noted that the ends of the wicks 23 and 33 both enter the main reservoir 11 so that both wicks are fed from the same source so that both the wick-burner and torch may be used as long as there is burning fluid in the reservoir. By inverting the reservoir it may be readily filled to the desired extent and the outer casing replaced, thus avoiding the necessity of plug closed filling-openings in the reservoir. In use the wick-burner is lighted by turning the wheel 19 so as to throw a spark from the flint 16. Then if it is desired to use the torch, the lighter will be tilted and held so that the flame from the wick-burner will impinge against the outer end of the torch, with the result that the torch becomes heated, thus vaporizing the liquid fuel in the end portion of the wick 33 in the torch and developing sufficient gas pressure to cause gas to issue from the opening 35, the issuing gas becoming ignited from the flame of the wick-burner and burning as a long flame which is directed in a downward direction and which is suitable for lighting a pipe. When in the closed position the lower edge of the rear end of the cover 29 impinges upon the lip 28 of the spring so as to hold the cover in closed position, but when the cover is swung to open position it will lock on the said lip and be held in its open position as shown in Figs. 2 and 3.

The plug 38 by mechanical pressure on the wick 33 effectively serves to prevent the vapor-

ized fluid or gas under pressure in the gas chamber 36 from passing out of the inner end of the said tube 32 into the main reservoir 11, without preventing the passage of fluid by capillary action from the reservoir 11 through the wick 33 into the said tube, thus enabling pressure to be built up in the gas chamber 36 for expelling the gas or vaporized fluid through the perforation 35 for the projection of a relatively elongated flame.

This construction avoids the overflowing of the main reservoir 11 when being filled as it is open and is clearly visible to the filler.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A lighter comprising: a main reservoir; a burner fed with fuel from said main reservoir; a torch-reservoir including a torch adjacent said burner, which torch is adapted to be heated by the flame from said burner; said torch-reservoir having passage-means communicating with said main reservoir; and means constructed and arranged to automatically cause a supply of fuel to pass from said main reservoir to said torch-reservoir and to automatically prevent substantial leakage of fuel from said torch-reservoir back into said main reservoir during operation of said torch, whereby when said torch and fuel therein is heated, fluid pressure is developed in said torch which is substantially greater than the pressure in said main reservoir.

2. A lighter comprising: a main reservoir; a

burner fed with fuel from said main reservoir; a torch-reservoir of very small capacity compared to the capacity of said main reservoir and including a torch adjacent said burner, which torch is adapted to be heated by the flame from said burner; said torch-reservoir having passage-means communicating with said main reservoir; and wick-means constructed and arranged to automatically cause a supply of fuel to pass from said main reservoir to said torch-reservoir and to automatically prevent substantial leakage of fuel from said torch-reservoir back into said main reservoir during operation of said torch, whereby when said torch and fuel therein is heated, fluid pressure is developed in said torch which is substantially greater than the pressure in said main reservoir.

3. A lighter comprising: a main reservoir; a burner fed with fuel from said main reservoir; a torch-reservoir formed as a relatively long tube of relatively-small diameter and including a torch adjacent said burner, which torch is adapted to be heated by the flame from said burner; said torch-reservoir having passage-means communicating with said main reservoir; and wick-means extending from adjacent said passage-means, along inside said torch-reservoir to a location adjacent the end of said torch, said wick-means having a portion under mechanical pressure to permit capillary action to feed fuel from said main reservoir to said torch reservoir and to prevent substantial leakage of fuel from said torch-reservoir back into said main reservoir during operation of said torch, whereby when said torch and fuel therein is heated, fluid pressure is developed in said torch which is substantially greater than the pressure in said main reservoir.

WILLIAM E. EVANS.
